[57] CLAIM

The ornamental design for a electrical connector for
temperature measuring equipment, as shown and de-
scribed.

DESCRIPTION

FIG. 1 is a front and lower left perspective view of an
electrical connector for temperature measuring equip-
ment showing our new design;

FIG. 2 is a right side elevational view thereof;

FIG. 3 is a top plan view thereof; and,

FIG. 4 is a rear elevational view thereof.

FIG. 1

FIG. 2

FIG. 3

FIG. 4
